TANK UNIT FOR A STEAM CARPET CLEANING MACHINE

Jerry R. Kent, Fresno, and Willie D. Kent, Clovis, Calif.,
assignors to Rug Doctor Inc.

Filed Oct. 29, 1973, Ser. No. 410,972

Term of patent 14 years

Int. Cl. D7—05; D15—05
U.S. Cl. D7—166

FIG. 6.

FIG. 8.

FIG. 1 is a side elevation of the tank unit for a steam carpet cleaning machine showing our new design.

FIG. 2 is a front elevation of the tank unit.

FIG. 3 is another side elevation of the tank unit.

FIG. 4 is a rear elevation of the tank unit.

FIG. 5 is a top plan view of the tank unit.

FIG. 6 is a bottom plan view of the tank unit.

FIG. 7 is a perspective view of the tank unit.

The elements which are shown in broken lines in FIGS. 1, 3, 6 and 7 are for illustrative purposes only and form no part of the claimed design.

We claim:

The ornamental design for a tank unit for a steam carpet cleaning machine, as shown and described.
